UNITED STATES PATENT OFFICE.

PETER McDANIEL AND WILLIAM F. KERNODLE, OF FRANKFORT, INDIANA; SAID
McDANIEL ASSIGNOR TO BENJAMIN F. JONES, OF FRANKFORT, INDIANA.

PRIMING DEVICE FOR EXPLOSIVE-ENGINES.

1,064,150.

Specification of Letters Patent. Patented June 10, 1913.

Application filed April 24, 1912. Serial No. 692,958.

To all whom it may concern:

Be it known that we, PETER McDANIEL and WILLIAM F. KERNODLE, citizens of the United States, residing at Frankfort, in the county of Clinton and State of Indiana, have invented certain new and useful Improvements in Priming Devices for Explosive-Engines, of which the following is a specification.

10 The present invention relates to a priming device for supplying a charge of gasoline or other fuel to the cylinder of an internal combustion engine before the crank-shaft of the same is turned for starting the engine.

An important object of this invention is to provide a device of the above mentioned character, having novel adjustable means whereby the amount of fuel supplied to the explosive cylinder may be regulated to suit the particular conditions.

20 A further object of the invention is to provide a priming device of the above mentioned character, adapted to be secured to the dash-board of an automobile or the like, so that the same may be quickly and easily operated without causing the driver to leave his seat.

25 A further object of the invention is to provide a device of the above mentioned character, which is manually operated to discharge the gasoline or the like therefrom and automatically operated upon being released to cut off the flow of the fuel.

35 A further object of the invention is to provide a priming device of the above mentioned character, which is neat in appearance, simple in construction, durable, and cheap to manufacture.

40 Other objects and advantages of the invention will be apparent during the course of the following description.

In the accompanying drawings forming a part of this specification and in which like numerals are employed to designate like parts throughout the same, Figure 1 is a side elevation of the priming device, Fig. 2 is a central longitudinal vertical sectional view through the same, showing the valve stem in its lower position, and, Fig. 3 is a similar view showing the valve stem in its elevated position.

In the drawings wherein for the purpose of illustration, we have shown a preferred embodiment of our invention, the numeral 1

designates an upstanding preferably cylindrical body portion of a main shell, having its upper and lower ends normally closed by removable heads 2 and 3, having screw-threaded engagement therewith. The main shell is divided into a fuel holding chamber 4 and a discharge chamber 5, by a vertically adjustable partition 6. This partition may be held against accidental movement by proper frictional engagement with the inner surface of the shell 1 or it may have screw-threaded engagement therewith. The partition 6 is made vertically adjustable so that the size of the discharge compartment 5 may be varied, depending upon the size of the engine in connection with which the primer is to be used. It is thus seen that the partition 6 after being properly vertically adjusted, remains permanently in such adjusted position as long as it is being used with the same engine.

The numeral 7 designates an air inlet pipe having its upper end passing through the head 2 and its lower end passing through the partition 6, for supplying air into the discharge chamber 5.

The numeral 8 designates a reciprocatory valve stem, which extends axially within the main shell and has its upper end passing through an apertured boss 9 formed upon the upper head 2. Outwardly of this apertured boss 9 the valve stem 8 is pivotally connected with the swinging lever 10, as shown at 11. This swinging lever is in turn pivoted between its ends with a fixed support 12, as shown at 13. The lever 10 is manually operated and is provided at its free end with a push button 14, as shown. It is thus seen that when the outer or free end of the lever 10 is depressed, the valve stem 8 will be elevated. When the lever 10 is released, it and the valve stem 8 are automatically returned to their normal positions by a compressible coil spring 15, surrounding the upper portion of the valve stem 8 within the main shell and having its upper end in engagement with the head 2 and its lower end in engagement with a ring 16, which is held against movement in one direction by a transverse pin 17. The partition 6 is provided centrally thereof with an opening 18, having its wall curved in vertical cross-section, as shown, for snugly receiving a vertically adjustable ball-valve 19. This ball-

110

valve is provided with a diametrically extending screw-threaded opening 20 formed therethrough to receive a screw-threaded portion 21 of the valve stem 8. It is thus seen that by rotating the ball-valve 19, it may be moved longitudinally of the valve stem 8, subsequently to which it is locked in its new position by a clamping ring 22, having a screw-threaded opening for receiving the screw-threaded portion 21 of said valve stem. The ball-valve 19 is disposed below the partition 6 and is seated for closing the opening 18 by an upward movement of the same and the valve stem 8. The lower head 3 is provided centrally thereof with a depending boss 23, provided with a discharge opening 24, which leads at its upper end into an inverted conical opening 25.

The numeral 26 designates a pipe suitably connected with the apertured boss 23 and also connected with the manifold inlet pipe of the internal combustion engine. A manually operated cut-off valve (not shown) is connected in the pipe 26, which valve is open when the engine is being primed and closed when the engine is in operation, to prevent the pressure from the engine from passing into the discharge chamber 5. At its lower end the valve stem 8 has a conical valve 27 suitably connected therewith, adapted to be seated by a downward movement in the opening 25 to completely close the same. The upper head 2 is provided with inlet opening 28 through which the gasoline or other fuel is fed into the main shell, such opening being normally closed by a removable cap 29.

The device is preferably attached to the dash-board 28 of an automobile or the like, by means of brackets 29, which are rigidly connected with the shell 1, and bolts 30 passing through such brackets and the dash-board 28.

The operation of the device is as follows: Assuming that the fuel holding chamber 4 is filled with gasoline or the like, such gasoline will pass through the opening 18 in the partition 6 to fill the discharge chamber 5 with the same. The valve 27 is now seated, thus preventing the discharge of the gasoline from the chamber 5. When it is desired to prime the engine, the cut-off valve (not shown) connected in the pipe 26 is opened, and the button 14 carried by the lever 10, is depressed, thus forcing that end

of the lever downwardly and elevating the valve stem 8. When this is done the ball-valve 19 closes the opening 18 and the valve 27 is unseated, whereby the gasoline is free to pass through openings 25 and 24 to the pipe 26, from which it gravitates to the manifold pipe. The operator retains the button 14 depressed for a sufficient length of time to allow of the discharge of the gasoline from the chamber 5, subsequently to which he releases the same, whereby valve stem 8 is automatically moved downwardly, valve 27 seated, and ball-valve 19 unseated. The discharge chamber 5 is again filled with gasoline from the holding chamber 4 and the priming device is again ready for use.

It is to be understood that the form of our invention herewith shown and described, is to be taken as a preferred example of the same, and that certain changes in the shape, size, and arrangement of parts may be resorted to without departing from the spirit of the invention or the scope of the subjoined claim.

Having thus described our invention, we claim:

In a priming device of the character described, a main shell, heads closing the upper and lower ends of the shell, the lower head being provided with a discharge opening having a conical portion serving as a valve seat, a horizontal partition plate vertically adjustably mounted within said main shell and provided with a substantially hemispherical central opening, a reciprocatory rod extending longitudinally within said main shell and provided near its lower end with screw-threads, a ball-valve rotatably mounted upon the screw-threaded portion of the rod, a conical valve connected with the lower end of the rod and adapted for movement into and out of engagement with the conical valve-seat, a coiled spring surrounding the reciprocatory rod and engaging the upper head, and a manually operated lever pivotally mounted upon the upper head and connected with the reciprocatory rod.

In testimony whereof we affix our signatures in presence of two witnesses.

PETER McDANIEL.

WILLIAM F. KERNODLE.
